UNITED STATES PATENT OFFICE.

CHARLES A. GOOZEY, OF PROVIDENCE, RHODE ISLAND, ASSIGNOR TO B. A. BALLOU & COMPANY INC., OF PROVIDENCE, RHODE ISLAND, A CORPORATION OF RHODE ISLAND.

BUTTON-FASTENER.

1,237,326.

Specification of Letters Patent. Patented Aug. 21, 1917.

Application filed February 19, 1917. Serial No. 149,455.

To all whom it may concern:

Be it known that I, CHARLES A. GOOZEY, a citizen of the United States, and resident of the city of Providence, in the county of

5 Providence and State of Rhode Island, have invented certain new and useful Improvements in Button-Fasteners, of which the following is a specification.

This invention relates to fasteners for 10 buttons more particularly for shirt stud buttons and the like, and this invention has for its object to provide a bodkin which is slidably mounted in the eye of the button shank, said bodkin comprising two spaced apart 15 resilient arms provided with a reduced neck portion whereby the bodkin may be frictionally and releasably retained in the middle of the bodkin and the end of the bodkin is turned at substantially a right angle to the 20 axis of the body thereof, whereby it may be slid through the eye to the end and then swung down substantially in line with the shank of the button to be readily passed through the button-hole.

25 The invention further consists in the provision of a bodkin of the class described having one end offset out of line with its body portion and then turned back at substantially a right angle to the axis of the body 30 thereby providing a crook neck whereby the bodkin may be swung down in direct alignment with the axis of the shank so as to reduce to the minimum the frictional resistance of drawing the bodkin through a stiffened button hole at the point where it connects to the eye of the button shank.

A further object of the invention is to turn both ends of the bodkin off at an angle to the axis thereof whereby the bodkin may be operated from either of its ends.

40 With these and other objects in view, the invention consists of certain novel features of construction, as will be more fully described, and particularly pointed out in the 45 appended claims.

In the accompanying drawings:

Figure 1—is a side elevation showing the bodkin as located in the eye of the shank and set at right angles to the shank.

50 Fig. 2—shows the bodkin as having been slid through the eye to the end thereof and then turned down in line with the shank.

Fig. 3—is the same as Fig. 2 but turned

at 45° thereto showing the spaced apart form of resilient arms and the reduced neck 55 portion near the middle of the body of the bodkin.

Fig. 4—is a view showing a modified form of bodkin where the end is turned at right angles to the axis thereof without 60 providing the crook neck as that illustrated in Figs. 1 and 2.

Fig. 5—shows the bodkin as having both 65 its opposite ends turned at substantially a right angle to the body thereof.

Fig. 6—is an enlarged view showing a 70 piece of wire as split and its arms separated and then contracted substantially at its middle portion to form a reduced neck.

Fig. 7—is a sectional view on line 7—7 75 of Fig. 6.

Fig. 8—shows a bodkin formed by bending a length of wire upon itself forming two 80 resilient spaced apart arms with a reduced neck portion, the ends of the wire being 75 connected together by a pointed head member.

Referring to the drawings, 10 designates the button head which may be formed of any suitable shape or size and of any suitable 85 material, that shown being more particularly designed for use as a stud button to be worn in shirt fronts and the like, this button being provided with a shank member 11 having an eye 12 formed therein. 85

The construction of the bodkin member 13 which is the essential feature of this invention may be varied somewhat to suit conditions and requirements. One construction is to employ a length of wire split longitudinally through its middle at 14 nearly the length thereof, leaving integral portions at either end, then separating these split portions forming two resilient arms 15 which are spread sufficiently so that they may be 95 readily forced through the eye of the shank but will exert a slight frictional resistance. The middle portion 16 of this bodkin is reduced forming a narrow neck or recess into which the wire of the shank eye will 100 snap and be releasably retained to hold the bodkin centrally across the back of the button. Rather sharp shoulders 17 are formed on one side of this notch or neck so as to prevent the bodkin from being readily 105 forced through in this direction. The end

of the bodkin which is provided with the abrupt shoulders 17 is provided with a piercing head 18 sharpened to be readily forced through the button-hole of the starched shirt front.

The opposite end of this bodkin is preferably offset as at 19 out of line with the axis of the body portion then turned back as at 20 at substantially a right angle to the axis of this body portion and is provided with an enlarged head 21 whereby this bodkin may be swung down in line with the plane of the shank 11 and the axis of the body portion will hang substantially in line with the longitudinal axis through the shank.

By the offsetting of this portion 19 it will be seen that a nicely rounding, tapering or wedging effect is produced whereby the lips of the button-hole are readily opened or forced apart to permit the shank portion of the button to enter thereinto.

I do not wish to be limited to the offsetting of this end portion, as in some instances the end of the bodkin may be turned off at an angle to the body portion thereof as at 22 without first offsetting the same from the plane of the body portion, as best illustrated in Fig. 4. Then again in some instances it is found desirable to turn both of the opposite ends of the bodkin at an angle to the body portion thereof as at 23, see Fig. 5, so that the same may be operated from either end if desired.

Neither do I wish to be restricted to the forming of the resilient arms of the bodkin by splitting the wire through the center thereof as illustrated in Fig. 6, as in some cases the body may be formed by separate wires bent into the desired shape with their ends secured together, or a single wire may be bent upon itself in the desired form as illustrated in Fig. 8.

I have illustrated a number of means whereby my invention may be carried out, but I do not wish to limit myself to any of these specific constructions as various changes in form and shape may be necessary, but I desire it to be understood that I reserve the privilege of resorting to all the mechanical changes to which the device is

susceptible, the invention being defined by the appended claims.

I claim:

1. In a button fastener, a bodkin comprising two spaced apart resilient arms adapted to be passed frictionally through the eye of a button shank, said arms provided with a reduced neck portion near the middle portion of the bodkin, one end of the bodkin being turned at an angle to the body portion whereby it may be swung down substantially in line with the button shank.

2. In a button fastener, a bodkin comprising two spaced apart resilient arms adapted to be passed frictionally through the eye of a button shank, and arms provided with a reduced neck portion near the middle portion of the bodkin, one end of the bodkin being bent off at an angle to the axis of its body portion and provided with a head which upon engaging the button shank determines the relative axial alignment of the bodkin and limits its swinging movement in one direction.

3. In a button fastener, a bodkin adapted to pass frictionally through the eye of a button shank, a reduced neck portion near the middle of the bodkin, one end of said bodkin being first offset out of line with the body thereof and then turned at substantially a right angle to the axis of the body whereby the bodkin may be swung down substantially in line with the button shank.

4. In a button fastener, a bodkin formed of a wire whose body is split longitudinally for a portion of its length and the split portion separated to form resilient arms both adapted to be slightly compressed upon being forced through the eye of the button shank, a reduced neck portion near the middle of the bodkin for frictionally retaining the button shank, one end of the bodkin being bent off at an angle to permit its being swung down out of line with the axis through the eye of the shank.

In testimony whereof I affix my signature in presence of a witness.

CHARLES A. GOOZEY.

Witness:

HOWARD E. BARLOW.
